UNITED STATES PATENT OFFICE.

ERICH H. LICHTENBERG, OF MILWAUKEE, WISCONSIN, ASSIGNOR TO KOEHRING COMPANY, OF MILWAUKEE, WISCONSIN, A CORPORATION.

BATCH-BOX APPARATUS.

Application filed June 6, 1922. Serial No. 566,362.

To all whom it may concern:

Be it known that I, ERICH H. LICHTENBERG, a citizen of the United States, residing at Milwaukee, in the county of Milwaukee and State of Wisconsin, have invented 5 certain new and useful Improvements in Batch-Box Apparatus, of which the following is a specification.

It is known that one of the present 10 expeditious methods of handling aggregates supplied to mixing machines used in conjunction with paving roads or the like, is to utilize an industrial railway, the bodies of the cars of which constitute batch boxes. 15 These cars loaded with certain of the aggregates are run up to the place where the paving is being laid, the batch boxes are hoisted off the car trucks, moved over a loading skip or similar loading device on 20 the mixer and discharged into the latter, after which the empty box is returned to the car or truck and goes back to the source of supply for a new batch of materials.

The improvements of this invention are 25 preferably used in conjunction with a crane carried by a mixing machine, for handling the batch boxes to lift them off of the cars, shift them over the loading skip of the mixer, empty or discharge them and re- 30 turn them to the car for reloading.

My invention involves several phases of construction of apparatus such as above outlined. One feature of the invention resides in the mounting of the crane so that it is 35 primarily supported by one of the traction members of the mixing or other machine by which it is carried, instead of being mounted upon the frame of the machine, which may be a tiltable frame. By this 40 manner of mounting the crane the same is supported practically directly over the surface on which the machine which carries it operates.

A second feature of the invention is to 45 provide what may be termed a single line control in the form of a cable by which the batch box grappling or hoisting tackle devices may be operated so as to open the batch box for discharging action, and for 50 closing it thereafter.

The third feature of the invention has 55 been to so design the batch box grappling or engaging parts used in connection with the hoisting means of the crane, that a single operator may readily engage the

grappling means with the batch box, while standing at one side of the latter. At the present time at least two men are employed for the purpose stated.

Still another feature of the invention resides in the provision of a batch box which itself embodies a novel construction particularly adapted for the work referred to.

It is to be understood that my invention is not limited in its utility as regards the 60 several improvements above referred to, to the particular class of machine which I have specifically described. The several instrumentalities of the improvements possess advantages for use with other kinds of 65 machines where cranes and dumping boxes are 70 of advantage.

In the accompanying drawings;

Figure 1 is a side view, partly broken away, of what is known as a paving mixer 75 equipped with a loading skip at one end and showing a crane and batch box apparatus for use in association with said skip.

Figure 2 is a front view of the truck and traction devices of the machine showing 80 more fully how the mast of the crane is stepped or mounted upon one of the multi-plane traction devices.

Figure 3 illustrates a side view of a batch box and grappling devices and tackle embodying my invention. 85

Figure 4 is a diagrammatic view showing the manner of looping the cable or hoisting line with pulleys on the crane and on the cross piece of the grappling apparatus. 90

Figure 5 is an end view of the parts shown in Figure 3.

Figure 6 is a detail view of a stop construction which I employ in a modified form of my apparatus, as illustrated in Figure 7. 95

Figure 7 is an end view of apparatus of the type of Figures 3 and 5, slightly modified in its construction.

Figure 8 is a diagrammatic view showing the method of looping the hoisting line 100 about the pulleys as used in the construction of Figure 7.

It is not deemed necessary to describe in detail the machine in conjunction with which my improvements are employed. It 105 suffices to know that my machine comprises a frame or body 1 mounted on traction multiplanes 2, preferably by a rocker bearing 3, seen best in Fig. 2. A loading skip 4 for raising the concrete aggregates and charg- 110

ing them into a concrete mixer, not shown, is used. The end of the machine equipped with the skip 4 has the crane and grappling apparatus of my invention applied thereto.

5 This crane includes the mast 5 which is stepped upon an arm 6 pivoted to the frame 1 at 7, and directly supported upon a bracket 8 carried by one of the multiplanes 2.

The mast 5 is equipped with the boom 9 10 braced by a guy rod 10, and at the base of the mast 5 is a winding drum 11, the cable 12 of which winds about in opposite directions and leads off to some suitable power driving means which enables the mast 5 to 15 be driven positively in either of opposite rotative movements, for swinging the boom 9 in corresponding directions to carry a batch box from an industrial car to the skip 4, and back again.

20 The machines of my invention, as generally depicted in Figure 1, are so large, having a capacity as large as fifty-six cubic feet, that power mechanism is necessary for preferred operation of machines of such 25 size.

The batch box 13 employed by me comprises a body having the bottom dumping doors 14. Connected with the doors 14 are links 15 which lead to the upper portion of 30 the sides of the batch box, as seen in Fig. 3, and are attached to loops or eyes 16, the peculiar form of which is best seen in Fig. 5.

The ends of the batch box are provided with keepers 17 of somewhat U form rigidly secured thereto.

40 The hoisting means for the batch box 13, as per my invention, comprises the constructions shown in Figures 3 to 8 inclusive, rather than the construction which is illustrated in Fig. 1, which forms the subject matter of an application for patent separate

45 from this one. In general principle the hoisting line control, however, is the same as shown in Fig. 1, where the hoisting cable 18 is seen as passing over a wheel 19 on top of the frame 20 of the machine, down thru a hollow portion of the mast 5, under a wheel 21, thence out over a wheel 22 on the upper end of the boom, thence down over a

50 guide wheel on a cross piece 23 forming a part of the supporting and grappling means for the batch box. From the wheel 24 the cable or line 18 passes up around the second guide wheel coaxial with the wheel 22, 55 thence down around the second guide wheel coaxial with the guide wheel 24 on the member 23, thence up to a point of attachment 25 at the upper end of the boom. As shown best in Figs. 3 and 5, my method of passing

60 the hoisting cable 18^a about the guide wheels 22^a, 22^b, and 22^c, on the boom 9, and certain guide wheels 24 on the cross-piece 23, is much the same as previously described except that the line is finally secured to the

65 cross-piece 23 and is looped three times at

the upper end of the boom and twice about the guide wheels of the member 23, all in a self evident manner on reference to Fig. 4. Also in my construction of Figs. 3 and 5, I support the batch box in two ways. In the 70 first place the cross-piece 23 is a door supporting bar or member controlling the opening and closing of the door owing to the provision of chains 23^a which connect said member 23 with hooks 26 adapted to engage 75 in the loops or eyes 16 connected with the doors 14. In order that one man standing at a side or end of the batch box may manipulate the hooks 26 to engage them with the members 16, I utilize a handle or bail 27 of 80 U form which is rigidly attached to the hooks 26 and capable of rocking or tilting them to simultaneously engage them with the said parts 16.

Keepers 17 before mentioned are engageable by a second supporting bar 28 having seats in its opposite ends preferably to receive the keepers 17 when said bar is shifted lengthwise to cause its ends to be received by said keepers. On the bar 28 is carried

the block 29 that carries the grooved guide wheel 30 about which the cable 18^a is passed according to the method shown in Fig. 4. The operator who is to manipulate the handle or bail 27 may also readily manipulate 95 the second supporting bar 28, which may be called the keeper engaging bar for the batch box 13. Connecting the upper end of the boom 9 and the block 29, or the bar 28, in practical effect, are the stop chains 31, two

100 of which are preferably employed so that the upper supporting bar or cross-piece 23 and guide wheel 30^a mounted thereon may be disposed therebetween. The cable in the construction now described is attached to 105 the bar 23 at 32.

With the construction set forth as above, it will be evident that if the engaging and supporting parts of the grappling means are carried over the batch box 13 as it rests 110 upon the industrial car, the operator may readily grasp the engaging bar 28, and the bail 27, as the cable 18^a is slackened to lower these parts over the car. An uphaul on the cable 18^a will then lift the box 13 with its 115 load or contents, and by throwing into operation proper control means, the drum 11 may be caused to turn by the cable means 12 connected thereto, whereby to turn the mast 5 and swing the boom 9 to bring the 120 box 13 over the skip 4. The operator thereupon slacks out the cable 18^a to lower the apparatus to bring the batch box 13 down almost into the skip 4. The chains 31 are sufficiently long and may be adjustable, so that as the batch box reaches about the position shown in Fig. 1, the chains 31 become 125 taut when the cable 18^a is laid out a sufficient amount. Thereupon the downward progress of the box 13 is stopped and the 130

further slackening of the cable 18^a permits the supporting cross piece 23 to lower thus lowering the hooks 26 and links 15 and permitting the doors 14 to open and dump the contents of the box. An inhaul of the cable 18^a now closes first the doors 14 by uplifting the supporting cross member 23, and when the doors are closed further movement on the cable 18^a will exert a pull on the engaging bar 28 cooperating with the keepers 17, whereupon the boom 9 may be swung back over the industrial car body or truck and the batch box lowered into place on the latter to be returned to the place of supply of materials and be reloaded.

Referring now to the construction in Figures 6, 7, and 8. It will be observed that a large number of the parts illustrated are substantially the same as shown and described hereinbefore and are correspondingly numbered therefore. In the modified form, however, I provide on the boom 9, preferably dependent from the outer extremity thereof, a stop bracket 34 arranged so that its lower end may abut with the member 23 at a certain point in the upward movement of the latter. The hoisting drum cable 18^a is passed about guide wheels on the upper outer end of the boom and on the lifting member 23, substantially as illustrated in the diagrammatic view Fig. 8. It will be apparent that by the operation of the cable 18^a the batch box 13 may be elevated a certain distance without dumping.

35 When the batch box is disposed above the place where it is to be dumped by hauling in on the cable 18^a, the box and its closed doors will be elevated until the crosspiece or bar 23 abuts with the stop bracket 34. 40 When this abutment takes place the upward movement of the doors will cease because the doors are primarily connected with the member 23. Further inhaul on the cable 18^a will then cause the body of the batch box 13 45 to continue its upward movement and such movement relative to the doors 14 will cause an opening or dumping action of the doors in relation to the body of the box. The relative movements of the parts are shown in 50 Fig. 7 where the dotted lines illustrate the member 23 as having reached its upper limit of movement and the additional dotted lines show the batch box body elevated some distance after the member 23 comes to a stop 55 enabling the dumping action of the doors 14 to take place. The arrangement of the parts and the construction of Figs. 6 to 8 is especially adapted for use where it is desired to dump the batch box 13 at a point which 60 is higher in elevation than the place from which the batch box is removed from the industrial car truck of which it forms the body.

The principal effects of the several constructions of my invention are to employ

the cable as a single line operating means for raising the batch box from its car, shifting it from the place where it is to be dumped and then cause a relative movement of the body of the box and its doors 70 so that the doors assume an open position in respect to the box and cause dumping of its contents. The relative movement of the doors and the batch box body may be established in either of the two ways shown 75 in the drawings, and possibly other methods of a corresponding nature. That is to say the opening of the batch box may be caused to take place incident to a limiting of the downward movement of the box body and 80 permit additional downward movement of its doors, or by permitting a limited upward movement of the doors and a continued or further movement of the batch box body 85 after the doors have ceased to move upwardly therewith. The single line control of the operation of the batch box in the manner specified is of obvious advantage in simplifying the entire control of the handling of the materials in said box and 90 the manner of connecting the engaging hooks 26 and the relative arrangement of the engaging bar 28 makes for a saving of labor in the handling of the batch box, as 95 one man can readily attend to this particular work while working from one side of the box, in an evident manner.

Having thus described my invention, what I claim as new and desire to secure by Letters Patent, is;

100

1. Batch box handling apparatus comprising a hoisting cable, a batch box comprising dumping doors and operative connections intermediate the doors of the batch box and the said cable and intermediate the said cable and the batch box body together with means to act on one of said connections whereby on proper movement of the cable relative movements may be imparted to the batch box body and its doors to open 110 the same for dumping action.

2. In combination, a hoisting and dumping cable, batch box apparatus comprising a batch box and dumping doors, grappling devices intermediate the cable and the batch box, and intermediate said cable and the doors, in both instances for detachable cooperation with the box and said doors, and means cooperative with the connections between the cable and the batch box and its doors such that movement of the cable is adapted to impart relative movement to the batch box body and the doors to effect dumping of the latter.

115

3. In combination, a hoisting and dumping cable, batch box apparatus comprising a batch box and dumping doors, separate grappling devices intermediate the cable and the batch box, and intermediate said cable and the doors, in both instances for de-

130

tachable co-operation with the box and said doors, and a controlling member arranged to act on one of the grappling devices such that movement of the cable is adapted to 5 impart relative movement to the batch box body and the doors to effect dumping of the latter and to effect further relative movement of said parts to cause closing of the doors for restoring the batch box to a 10 normal batch receiving condition.

4. In combination, a batch box and a dumping door therefor mounted thereon, a single line control mechanism for causing dumping action of the batch box thru the 15 opening of its door and for closing the door thereafter, comprising a cable, detachable connecting means intermediate the cable and the body of the batch box and other detachable connecting means intermediate 20 the cable and the door, and stop means cooperative with one of said batch box parts to limit its movement whilst the movement of the other is continued, whereby manipulation of the cable will cause a dumping of 25 the batch box and a further manipulation may cause a closing of the batch box.

5. In combination, a batch box apparatus comprising a box and a dumping door therefor, a single line controlling means for causing dumping action of the batch box and including detachable grappling devices connectible with the batch box body and with the said door, a cable so connected with the parts of the grappling devices as to cause 30 upon movement of the cable simultaneous movement of the batch box and its door, and means to limit the extent of movement of one of the parts of the batch box and door unit to enable the other part to continue movement while the first part is relatively stationary, all under the influence of 35 said cable to effect dumping of the box during operation of the cable.

6. In combination, a batch box apparatus comprising a box and a dumping door therefor, a single line controlling means for causing dumping action of the batch box and including detachable grappling devices connectible with the batch box body and with the said door, a cable so connected with the parts of the grappling devices as to cause 45 upon movement of the cable simultaneous movement of the batch box and its door, and means to limit the extent of movement of one of the parts of the batch box and door unit to enable the other part to continue movement while the first part is relatively stationary, to effect dumping of the box during operation of the cable, said grappling device parts and cable operating in a 50 reverse manner to cause certain relative movements of the batch box and door to close the box and thus restore it to normal receiving condition.

7. In combination, a batch box and dump-

ing door therefor, a crane comprising a boom, a hoisting and operating cable connected with the boom, a grappling device comprising an engaging bar detachably co-operating with the body of the batch box 70 and a hoisting cross-piece having a detachable connection with the door of the batch box, a connection intermediate such cross-piece and said engaging bar, and the cable, such that these parts may be caused to 75 move simultaneously and means for stopping the movement of one of the engaging bar and cross-piece parts aforesaid to enable the other part to continue its movement and thus obtain a relative movement 80 between the batch box and its door to effect opening of the latter under the control of the movement of the cable, a reversal of the movement of the parts being adapted to cause a closing of the door of the batch box. 85

8. Grappling apparatus for batch boxes comprising an engaging bar engageable with the body of a batch box and having guide wheels thereon, a hoisting cross-piece having hooks adapted to connect with doors of 90 a batch box and also equipped with guide wheels thereon, and a hoisting and operating cable wove about the guide wheels of said cross-piece and said engaging bar substantially as described. 95

9. Grappling apparatus for batch box hoisting purposes comprising door connecting hooks, a cross-piece from which said hooks are suspended, a handle connected to said hooks for simultaneous connection for 100 engaging the same with door parts, an engaging bar adapted to be engaged with the body of a batch box when the said hooks are connected with the said doors thereof, guide wheels on the engaging bar and on said 105 cross-piece, an operating cable wove around said guide wheels to place the cross-piece and engaging bar in suspension for raising or lowering the same together, and means for limiting the movement of one of the engaging bars and cross-piece parts so that the other part may move and thus controlling the relative movements of those parts of the batch box with which they are connected. 110

10. A batch box comprising dumping 115 doors, two hoisting parts, keepers on the body of said batch box adapted to be engaged by a hoisting part, and eyes or loops connected with the doors also to enable connection of the latter with a second hoisting part, and a single hoisting cable cooperative with both of said parts to control simultaneous movement thereof, and means to compel independent movement of the hoisting parts by said cable to control dumping and closing of the box. 120

11. In combination, batch box hoisting apparatus including a batch box comprising a body and dumping doors, the body equipped with keepers at opposite sides 125 129

thereof, eyes connected with the dumping doors of the box and located on other opposite sides of the latter, grappling means for detachable connection with the said eyes and said keepers, and including engaging bars to engage the keepers, hooks to engage said eyes, an operating handle connected with the hooks to control the simultaneous manipulation thereof, a cross-piece from which said hooks are suspended, an operating cable connected with the boom and movably connected with the engaging bar and with the said cross-piece which supports the hooks to cause simultaneous raising and

lowering movement of the engaging bar and cross-piece and any supported parts, and means to limit the movement of one of the cross-piece and engaging bar parts whilst the other continues to move to enable a relative movement between the batch box body and its doors to take place for dumping of the box, all under the action of said cable and other relative movement of the same character to cause a closing of the box by the action of said cable.

In testimony whereof I affix my signature.

ERICH H. LICHTENBERG.
